WOLFGANG MAX SCHULTZ, OF BERLIN-KARLSHORST, GERMANY, ASSIGNOR TO
SCHERING-KAHLBAUM A. G., OF BERLIN, GERMANY

WASHING DRUM FOR PHOTOGRAPHIC PICTURES

Application filed May 13, 1929, Serial No. 362,713, and in Germany May 19, 1928.

With the washing drums for photographic pictures, as used up to now, the drawback is encountered that, owing to the centrifugal action of the currents of the liquid in the drum, as caused by the rotation of this latter, the pictures are pressed against the inner wall of the cylindrical drum, in consequence whereof the pictures contact with one another and the fixing salt, as hypo-sulphite of sodium, therefore, is not washed out in a sufficient manner. These pictures tend, therefore, to become yellow, as well as spotty, in the course of time.

Endeavors have been made to obviate these drawbacks, for instance by providing the wall of the drum or cylinder with apertures of various sizes and shapes, as well as by providing above the drum or cylinder a spray for rinsing the pictures adhering to said wall.

The problem is solved by the present invention illustrated diagrammatically and by way of example on the accompanying drawing on which Figure 1 is a side-view of a washing apparatus having a washing drum designed according to this invention, Figure 2 is a side-view of this apparatus, Figure 3 is a similar representation showing the washing drum lifted, Figure 4 is a side-view solely of said drum, Figure 5 is a frontal view of the drum, and Figure 6 shows some details of the drum, drawn to an enlarged scale.

On the drawing, *d* denotes the drum, the circumferential wall of which is composed of radial portions *b* and oblique portions *a*, the transverse section of the drum resembling, therefore, a ratchet-wheel. The drum may consist of sheet-metal or of any other suitable material, and its end walls *f* are provided with openings which are circular in the example shown, but may also be designed as slots. Slots or circular openings *c* are also provided in the radial portions *b* of the drum.

The drum is located in a trough *g* supported by a frame *i*. The trough is filled with the washing liquid which enters into the drum through the frontal apertures and the apertures *c*. The currents of liquid en-

tering into the drum through the apertures *c* flow practically tangentially with respect to the circumference of the drum, and press the pictures tending to deposit on the wall portions *b* off into the interior of the drum where they are continually turned over and whirled around one another so as to be washed very thoroughly and uniformly.

The drum is provided with pivots *l* supported in open bearings on the trough, as shown in dotted lines in Fig. 2. The drum is rotated by means of an electromotor *r* also supported on the frame *i* and driving a worm *m* meshing with a worm-wheel *n* (indicated only by dotted lines in Figs. 2 and 3) coupled with a chain-wheel *o* driving another chain-wheel *p* by means of a chain *q*. The chain-wheel *p* is coupled by means of a shaft extending parallel to the drum and above it with small friction disks *s* which can contact with large friction disks *t* firmly connected with the drum. It is obvious that the electromotor rotates the drum by the intermediary of the members *m*, *n*, *o*, *q*, *p*, *s* and *t*.

The wheels *n* and *o*, as well as *p*, are attached to a rod *u* hinged at its lower end to a transverse member *i'* of the frame *i*. The rod *u* is connected by a rod *v* with a double-armed lever *w* pivoted at *w'* and provided near said rod *v* with a treadle *w'*, whereas its other end is connected by a rod *x* with a lever *y* secured to one end of a shaft *y'*. To this shaft are also affixed two arms *z*, one at the one end of said shaft, near the lever *y*, and the other at the other end of the said shaft. From the free end of each of said arms is suspended a link *z'* which is coupled with one of the journals *l* of the washing drum.

The drum is suspended from said links *z'*, and the pressure exerted by its weight is transmitted by the members *z*, *y'*, *y*, *x*, *w*, *v* and *u*, to the friction roll *s* which is thereby pressed upon the rim of the large friction disk *t*. Therefore, when the electromotor is in operation, the drum is rotated, as already described.

A set of such members as *u*, *v*, *w*, *x*, *y*, *z* is provided not only at the one frontal end of

the machine, but at the other frontal end also. The treadle w^2 extends from the one lever w to the other lever w , and the two rods u carry the longitudinal shafts s^1 to which the two small friction disks s are affixed. The ends proper of these rods are connected with one another by a bar u^1 with the aid of which, in conjunction with the treadle w^2 , the disks s can be withdrawn from the large disks t and simultaneously therewith the drum can be lifted, as shown in Fig. 3.

A certain part of the circumferential wall of the drum is designed as a flap h (Fig. 5). When this flap is opened (position drawn in dotted lines in Fig. 5) the pictures can be introduced into the drum and, of course, also removed from it.

In order to lift the drum out of the trough g , and to interrupt at the same time the frictional driving connection between the roll s and the disk t , the treadle w^2 is depressed in the direction of the arrow I whereby the double-armed lever w will be turned and simultaneously therewith the rod v will turn the rod u in the direction of the arrow II, in consequence whereof the roll s will be withdrawn from the disk t . The rear arm of the lever w will lift the rod x whereby also the arms y and z will be lifted and, thus, the drum will be withdrawn from the trough in the direction indicated by the arrow III.

When the pressure exerted upon the treadle ceases, all movable members return automatically into their former position.

I claim:

1. A washing apparatus for photographic pictures, comprising in combination with a trough, a drum, the peripheral wall of which is composed of radial portions having openings, and of oblique portions therebetween, said drum being rotatably supported in said trough.

2. A washing apparatus for photographic pictures, comprising, in combination with a trough, a drum, the peripheral wall of which is composed of radial portions having openings, and of oblique portions therebetween, and means for rotating said drum.

3. A washing apparatus for photographic pictures, comprising, in combination with a trough, a rotary drum, the peripheral wall of which is composed of radial portions having openings, and of oblique portions therebetween, a motor, and means for transmitting motion from said motor to said drum.

4. A washing apparatus for photographic pictures, comprising, in combination with a trough, a drum rotatably supported therein, the peripheral wall of which is composed of radial portions having openings, and of oblique portions therebetween, a friction disk connected with said drum, and means for transmitting motion from said motor to the said drum, a friction roll contacting

normally with said friction disk forming one of the motion transmitting means.

5. A washing apparatus for photographic pictures, comprising, in combination with a trough, a drum, the peripheral wall of which is composed of radial portions having openings, and of oblique portions therebetween, and means for rotating said drum, a friction disk connected with the drum and a friction roll contacting normally with said disk forming members of the motion transmitting means, a turnable rod having said roll attached to its free end, this rod being pivoted practically diagonally opposite to the said friction roll, a double-armed lever arranged below the said trough, a rod connecting the first-mentioned rod and said lever with one another, the arrangement being such that the friction roll is withdrawn from the friction disk when the second rod is subjected to a pull by the said lever, and means for lifting simultaneously therewith the drum out of the trough by the other arm of the said lever.

6. A washing apparatus for photographic pictures, comprising, in combination with a trough, a drum, the peripheral wall of which is composed of radial portions having openings, and of oblique portions therebetween, and means for rotating said drum, a friction disk connected with the drum and a friction roll contacting normally with said disk forming members of the motion transmitting means, a turnable rod having said roll attached to its free end, this rod being pivoted practically diagonally opposite of the said friction roll, a double-armed lever arranged below the said trough, a rod connecting the first-mentioned rod and said lever with one another, turnable arms from which the drum is suspended and maintained in proper position within the trough, and means for transmitting power from the other arm of the double-armed lever to the last-mentioned means.

7. A washing apparatus for photographic pictures, comprising, in combination with a trough, a drum, the peripheral wall of which is composed of radial portions having openings, and of oblique portions therebetween, and means for rotating said drum, a friction disk connected with the drum and a friction roll contacting normally with said disk forming members of the motion transmitting means, a turnable rod having said roll attached to its free end, this rod being pivoted practically diagonally opposite to the said friction roll, a double-armed lever arranged below the said trough, a rod connecting the first-mentioned rod and said lever with one another, the arrangement being such that the friction roll is withdrawn from the friction disk when the second rod is subjected to a pull by the said lever, and means for lifting simultaneously therewith

the drum out of the trough by the other arm of the said lever, turnable arms from which the drum is suspended and maintained in proper position within the trough, a shaft to which said arms are affixed, a third arm 5 at this shaft, and a rod connecting this arm with the other arm of said double-armed lever.

In testimony whereof I affix my signature.

WOLFGANG MAX SCHULTZ.
